AIR CONDITIONING

Alonzo W. Ruff, York, Pa., assignor, by mesne assignments, to Auditorium Conditioning Corporation, New York, N. Y., a corporation of New Jersey

Application December 19, 1933, Serial No. 703,136

29 Claims. (Cl. 62—6)

This invention relates to air conditioning, or what is sometimes called "comfort cooling," and provides a simplified arrangement of cooling mechanism and automatic controls therefor.

It has frequently been proposed to control the operation of a comfort cooling plant in response to dry bulb temperature. Such controls are not satisfactory because under certain conditions the dry bulb temperature may fall below the setting of the regulatory thermostat while the humidity is unduly high. The present invention avoids this difficulty by keeping the compressor in operation at a uniform rate when dry bulb temperature or relative humidity, or both, are above the maximum values set for each, and so regulating the device that when humidity is above its chosen value, and dry bulb temperature is below its chosen value, the temperature of the evaporator is reduced and at the same time the total refrigerative effect is reduced. As a consequence the refrigerative evaporator becomes very effective as a dehumidifier and relatively ineffective as a cooler.

From one point of view the action might be described as starving the evaporative system by limiting the amount of refrigerant fed thereto. The effect is to reduce the suction pressure and consequently the evaporator temperature, and at the same time reduce the total refrigerative effect.

From another point of view, the action might be described as reducing the effective area of the evaporator and at the same time reducing the suction pressure.

The invention may be embodied in various specifically different forms, three of which will be discussed with reference to the accompanying drawings, in which—

Fig. 1 is a diagrammatic elevation, partly in section, of the preferred embodiment of the invention.

Fig. 2 is a similar view showing a modification in which the thermostat does not control the motor which drives the compressor and in which the thermostat exercises a modulated control.

Fig. 3 is a similar view representing a modification of the arrangement shown in Fig. 1 in which the evaporator surface is not sub-divided as in Fig. 1.

Referring first to Fig. 1.

6 represents a housing through which a motor driven fan, diagrammatically indicated at 7, circulates air. The air enters the casing through an intake, indicated at 8, flows upward through the casing and is discharged by the fan at 9. In the casing 9 are two refrigerative evaporators 11 and 12. The suction connections 13 and 14 of the two evaporators lead to a common suction line 15, which is connected to the compressor 16. A high pressure line 17 leads from the compressor to a combined condenser and receiver, indicated at 18, from which the liquid line 19 leads by way of a strainer 21. The liquid line 19 supplies refrigerant to the coil 11 through an expansion valve 22 of the thermostatically controlled type. The thermostatic control is exercised by a bulb 23 in thermal contact with the suction connection 13. Pressure developed in the bulb 23 by rise of temperature tends to open the valve 22. The particular valve illustrated is one manufactured by the Detroit Lubricator Company under Patent 1,776,401, issued Sept. 23, 1930, but any suitable expansion valve, preferably thermally controlled, might be substituted.

The liquid line 19 also supplies refrigerant to the evaporator 12 through a similar expansion valve 24 having a thermostatic controlling bulb 25 on the suction connection 14. The liquid line 19 is not, however, connected directly to the expansion valve 24, but a solenoid actuated stop valve 26 is interposed, the stop valve being arranged to close when the solenoid 27 is energized.

The compressor 16 is driven at constant speed by a motor 28, which, in the example illustrated, is an electric motor. This motor is stopped and started by a starting mechanism 29, whose specific form is immaterial.

A dry bulb thermostat 31 and humidostat 32 are mounted in the room into which the fan 7 discharges. In the example illustrated they are of the electric switch type and receive current from the lines 33 and 34 through a branch 35. The humidostat 32 is connected by a line 36 with the starter 28 and conditions the starter to cause the motor 28 to run when humidity exceeds a chosen value. The thermostat 31 receives current through the same branch 35 and is connected by a branch 37 and line 38 with the starter 28 in such a way that if the dry bulb

temperature is above the chosen value the thermostat will condition the starter 29 to cause the motor 28 to run. Thus the motor runs if either temperature or humidity, or both, be above the respective values set for these quantities. The return line from the starter is shown at 39.

The thermostat 31 is also connected by a branch line 38 and return line 41 with solenoid winding 27. When the thermostat 31 responds to a temperature below the chosen value, and thus tends to permit the starter to stop the motor 28, it energizes the solenoid 27 and closes the valve 26. If at such time the humidostat 32 is calling for refrigeration, the motor 28 will run notwithstanding the action of the thermostat 31.

Assume that humidity and temperature are both above the chosen value, the motor 28 will run, the valve 26 will be open, and both evaporators 11 and 12 will be effective to cool and dehumidify the air. If the humidity alone falls below the chosen value, the system will continue to operate as before. If both humidity and temperature fall below the chosen value, the motor 28 will be stopped and refrigeration ceases. If temperature alone falls below the minimum value, valve 26 will be closed and the evaporator 12 will become inactive. Since the compressor 16 continues in action at its normal rate, the effect will be to reduce the suction pressure in the evaporator 11, and since the thermostatic control 23 will function to limit the superheat, the total quantity of refrigerant fed will be reduced. It follows that less refrigerant is evaporated in a smaller evaporator surface under a lower suction pressure. Consequently the total refrigeration is reduced but the temperature of the coil 11 is materially reduced. The effect is to intensify dehumidification and yet reduce the total refrigeration.

The scheme just described gives no modulation of the action when temperature is below the desired minimum. This result can be secured by the arrangement shown in Fig. 2 where parts similar to those shown in Fig. 1 are given the same reference numerals with the letter "a."

It will be observed that there is no thermostat corresponding to the thermostat 31 and no solenoid valve 26, 27. Consequently the starting and stopping of the motor 28a is controlled solely by the indications of the humidostat 32a. Adjacent the air intake 8a there is mounted the actuating bulb 45 of a thermostatic modulating valve whose motor element is indicated at 46 and whose valve element is indicated at 47. The valve 47 is interposed in the suction connection 13a. It could just as well be located in the suction connection 14a, it being immaterial which one of the two evaporators is controlled.

Pressure developed in the bulb 45 on rise of temperature operates through motor 46 to gradually open the valve 47. Thus as the temperature of air entering at 8a decreases the evaporator 11a is progressively shut down by throttling its suction connection. The effect of this is to reduce the suction pressure developed by the compressor 16a. The action is similar to that described with reference to Fig. 1 except that it is progressive.

It is not strictly necessary to subdivide the evaporator surface into two distinct units, as a single unit may be used and starved under low temperature conditions in the conditioning space to reduce its refrigerating effect and also its temperature. What actually happens is that with

the reduced flow of refrigerant a portion of the evaporator surface becomes inactive.

Such a structure is illustrated by way of example in Fig. 3. In this figure a number of parts 5 conform in detail to parts in Fig. 1, and are designated by the use of the reference numerals used on Fig. 1 but with the letter "b." Such parts as those numbered 6b to 9b, inclusive, 15b to 21b inclusive, and 26b to 41b inclusive.

In the housing 6b is a single evaporator 51. It has a suction connection 52 and a supply connection fed by an automatic expansion valve 53. The valve 53 conforms in structure to those previously described, and its operation is regulated by a thermostatic bulb 54 in thermal contact with the suction connection 52. The suction connection 52 is connected to the suction line 15b. The liquid line 19b is not connected directly to the expansion valve 53 but has two connections therewith, such connections being in parallel with each other. One of these connections is by way of a throttling valve 55. This valve is set to a flow capacity less than the normal demand of the evaporator 51 when the compressor 16b is operating at its normal constant speed. The other connection is controlled by the valve 26b. When the valve 26b is open the supply of refrigerant to the valve 53 is sufficient to meet the maximum demand of the coil 51.

As in the structure of Fig. 1, the motor 28 operates at constant speed whenever the thermostat 31b or the humidostat 32b calls for refrigeration, and is stopped only when both cease calling for refrigeration. However, if the thermostat 31b ceases calling for refrigeration while the humidostat 32b calls for refrigeration, the solenoid 27b will be energized and the valve 26b will be closed. Consequently, the supply of refrigeration to the evaporator 51 is limited to the capacity of the orifice at the valve 55, and since this is less than the normal evaporative capacity of the evaporator the suction pressure is reduced and the refrigerative effect is also reduced. While the entire evaporative surface is nominally active, the fact is that only a portion of the surface of the evaporator 51 is effective. Consequently, just as in the case of the structure of Fig. 1, dehumidification is intensified but refrigeration of the air is reduced.

The operative principles underlying all three embodiments are essentially similar, but various forms have been illustrated to indicate the breadth of the invention, and also to indicate different types of installation suitable for somewhat different conditions.

To indicate quantitatively conditions which may exist when the entire evaporative surface is effective and when only a portion of the evaporative surface is effective, the following tabulation, based on quantitative tests is given.

This tabulation shows two examples falling within the scope of the invention. In order to offer a strict comparison between conditions with fully effective evaporator and partially effective evaporator, the same dry bulb temperature and the same relative humidity are assumed for room conditions, neglecting the fact that automatic regulation implies variation of these quantities. The purpose of the examples is to demonstrate that shift in distribution between sensible heat tonnage and moisture condensation tonnage must occur as the result of using fully and partially effective evaporator. In each example column "A" gives conditions of fully effective evaporator

and column "B" conditions with partially effective evaporator.

	Example #1		Example #2	
	Full A	Partial B	Full A	Partial B
Room—dry bulb degrees	75	75	75	75
Room—relative humidity percent	60	60	50	50
Room—dew point	60.2	60.2	55.2	55.2
Grains of moisture/# in room air	78.5	78.5	66	66
Saturation temperature	54.5	47	52	43.7
Temperature of refrigerant	48.5	34	46	31.7
Capacity of refrigerating machine	1.18	0.85	1.13	0.80
Dry bulb air leaving unit	56.6	63.4	53.9	62.7
Relative humidity-air leaving unit	96	75	94	66
Dew point-air leaving unit	55.1	55.3	52.3	51.3
Grains of moisture/# air leaving unit	65.8	66.1	59	56.8
Air temperature drop through unit	18.4	11.6	21.1	12.3
Moisture removed through unit grains/# air	12.7	12.4	7.0	9.2
C. F. M. of air	500	500	500	500
Sensible heat tonnage	.84	.516	.94	.55
Moisture condensation tonnage	.34	.334	.19	.25
# moisture condensed per hour of continuous operation	3.86	3.79	2.16	2.84

It is important to observe that air leaving the unit is not saturated and carries fewer grains of moisture per pound of air than does the air in the room. The effect of progressive mixture with air in the room is to reduce the number of grains of moisture per pound of air in the room. This reduction of moisture, occurring as it does without a commensurate reduction of dry bulb temperature in the room produces a reduction of relative humidity which will ultimately reach the low setting of the humidostat and shut down the machine.

It must be remembered that comfort cooling units ordinarily are not used under conditions which preclude the access of heat to the cooled space, and that under normal conditions of use the removal of moisture results in reduction of relative as well as absolute humidity.

Stated differently, when air from the unit at higher relative humidity and lower temperature than the room air mixes with the room air, the relative humidity of the mixture is in practice lower than the relative humidity of the room air prior to such mixture.

It follows that although the humidostat 32 (or 32a or 32b) preferably responds to relative humidity rather than absolute humidity it can, and in practice does, shut down the machine periodically when operating under humidity control alone. When operating under humidity control the machine runs in cycles, the total periods of operation being longer than under thermostat control, without lowering the dry bulb temperature to an uncomfortable point because the temperature drop through the unit is less than when operating on a fully flooded coil as is the condition when the thermostat is in control.

While the regulation secured by the method and apparatus herein disclosed may not be as precise as that theoretically attainable by other methods, it does produce commercially satisfactory conditions. The simplicity of the installation and of the controlling mechanism commend it both from the standpoint of initial cost and from the standpoint of maintenance.

What is claimed is:

1. The method of regulating an air conditioning plant of the refrigerative type, including compressing means and a refrigerative evaporator in heat exchanging relation with air undergoing

conditioning, said evaporator being connected to supply refrigerant vapor to said means, such method comprising keeping the compressing means substantially uniformly in action, and reducing the effective area of the evaporator in response to reduction of temperature of the air in the conditioned space below a critical value whereby the temperature of the evaporator is reduced.

2. The method of regulating an air conditioning plant of the refrigerative type, including compressing means and a refrigerative evaporator in heat exchanging relation with air undergoing conditioning, said evaporator being connected to supply refrigerant vapor to said means, such method comprising keeping the compressing means substantially uniformly in action, and varying the effective area of the evaporator in response to variations of temperature of air in the conditioned space.

3. The method of regulating an air conditioning plant of the refrigerative type, including compressing means and a refrigerative evaporator in heat exchanging relation with air undergoing conditioning, said evaporator being connected to supply refrigerant vapor to said means, such method comprising keeping the compressing means substantially uniformly in action, and varying the effective area of the evaporator in response to variations of temperature of air in the conditioned space.

25 4. The method of regulating an air conditioning plant of the refrigerative type, including compressing means and a refrigerative evaporator in heat exchanging relation with air undergoing conditioning, said evaporator being connected to supply refrigerant vapor to said means, such method comprising keeping the compressing means substantially uniformly in action, and reducing the rate of evaporation of refrigerant in response to reduction of temperature of the air in the conditioned space below a critical value whereby the temperature of the evaporator is reduced.

35 5. The method of regulating an air conditioning plant of the refrigerative type, including compressing means and a refrigerative evaporator in heat exchanging relation with air undergoing conditioning, said evaporator being connected to supply refrigerant vapor to said means, such method comprising keeping the compressing means substantially uniformly in action, and varying the rate of evaporation of refrigerant in the evaporator in response to variation of air temperature in the conditioned space.

40 6. The method of regulating an air conditioning plant of the refrigerative type, including compressing means and a refrigerative evaporator connected to supply refrigerant vapor to said means, such method comprising, starting and stopping the compressing means in response to variation of atmospheric humidity in the conditioned space above and below a chosen value, causing said compressing means to operate uniformly when running, and reducing the effective area of the evaporator in response to reduction of temperature of the air in the conditioned space below a critical value whereby the temperature of the evaporator is reduced.

45 7. The method of regulating an air conditioning plant of the refrigerative type, including compressing means and a refrigerative evaporator connected to supply refrigerant vapor to said means, such method comprising starting and stopping the compressing means in response to variation of atmospheric humidity in the conditioned space above and below a chosen value, causing said compressing means to operate uniformly when running, and varying the effective area of the evaporator in response to variations of temperature of air in the conditioned space.

75 8. The method of regulating an air conditioning plant of the refrigerative type, including compressing means and a refrigerative evaporator connected to supply refrigerant vapor to said means, such method comprising starting and

stopping the compressing means in response to variation of atmospheric humidity in the conditioned space above and below a chosen value, causing said compressing means to operate uniformly when running, and reducing the rate of evaporation of refrigerant in response to reduction of temperature of the air in the conditioned space below a critical value, whereby the temperature of the evaporator is reduced.

8. The method of regulating an air conditioning plant of the refrigerative type, including compressing means and a refrigerative evaporator connected to supply refrigerant vapor to said means, such method comprising starting and stopping the compressing means in response to variation of atmospheric humidity in the conditioned space above and below a chosen value, causing said compressing means to operate uniformly when running, and varying the rate of evaporation of refrigerant in the evaporator in response to variation of air temperature in the conditioned space.

9. The method of regulating an air conditioning plant of the refrigerative type, including compressing means and a refrigerative evaporator connected to supply refrigerant vapor to said means, such method comprising controlling the compressing means in response to atmospheric temperature and humidity in the conditioned space, so as to operate the compressing means at a uniform rate when either or both temperature and humidity exceed chosen respective values and stop the compressor when both are below such values, and reducing the effective area of the evaporator when such temperature alone is below such chosen value.

10. The method of regulating an air conditioning plant of the refrigerative type, including compressing means and a refrigerative evaporator connected to supply refrigerant vapor to said means, such method comprising controlling the compressing means in response to atmospheric temperature and humidity in the conditioned space, so as to operate the compressing means at a uniform rate when either or both temperature and humidity exceed chosen respective values and stop the compressor when both are below such values, and reducing the rate of evaporating refrigerant when such temperature alone is below such chosen value.

11. The method of controlling an air conditioning plant of the refrigerative type including an evaporator and a constant speed compressor fed thereby, which method comprises keeping the compressor constantly in action, except when atmospheric temperature and humidity both fall below chosen minimum values; and while the compressor is running, varying the evaporator temperature and the total refrigerative effect in the same sense by varying the quantity of refrigerant evaporated in consonance with said temperature.

12. In a refrigerative air-conditioning system, the combination of refrigerative evaporating means; means for circulating air to be treated, over said evaporating means; a compressor fed by said evaporating means; means for driving said compressor at a substantially constant rate; condensing means for condensing vapor discharged by said compressor; and thermostatic means responsive to the dry bulb temperature of the treated air and effective upon a reduction of temperature thereof to reduce the temperature of at least a portion of the evaporating means and also the total refrigerative effect.

13. The combination defined in claim 12, in which means responsive to the humidity of the treated air is provided to control the starting and stopping of the means which drives the compressor.

14. The combination defined in claim 12, in which the thermostat responsive to dry bulb temperature and a humidostat responsive to the humidity of the treated air, conjointly control the means for driving the compressor and are arranged to keep said means in action when either or both the thermostat and the humidostat call for refrigeration.

15. The combination defined in claim 12, in which the evaporating means is subdivided and the thermostat responsive to dry bulb temperature functions below a critical value to terminate the supply of refrigerant to one subdivision.

16. The combination defined in claim 12, in which the evaporating means is subdivided and the thermostat responsive to dry bulb temperature controls the suction connection of one subdivision in such a way as progressively to open said connection on rise of temperature and progressively close it on fall of temperature, within chosen limits.

17. The combination defined in claim 12, in which the thermostat responsive to dry bulb temperature functions to restrict the rate of flow of refrigerant to said evaporating means when dry bulb temperature is below a chosen minimum.

18. The combination defined in claim 12, in which the evaporating means is constructed as a single unit, and is fed through an expansion valve of the thermally controlled type, there being two supply paths from said receiver to said expansion valve, one of which is constantly open and of capacity less than the capacity of the expansion valve, and the other of which is controlled by said thermostat and is closed thereby when the temperature of the treated air falls below a chosen minimum.

19. The combination defined in claim 12, in which the evaporating means is divided into two sections each fed independently of the other by a thermostatic expansion valve subject to temperature of the vapor leaving the sections of the evaporator, and in which supply of refrigerant to one of said expansion valves is controlled by a stop valve closed by said thermostat when the temperature of the treated air is below a chosen minimum.

20. The process of cooling and dehumidifying air which comprises causing air, which is to be conditioned, to circulate in heat exchange relation with a portion of an evaporator of a mechanical refrigerator and in heat exchange relation with another portion of the evaporator; causing all of refrigerant, flowing from one of the portions, to flow through the other whenever the refrigerator is in operation; and while refrigerant thus flows through the evaporator, causing a device to respond to a drop in dry bulb temperature of the air below a predetermined minimum while the humidity content of the air is above a predetermined minimum to vary the effectiveness of one of said portions of the evaporator.

21. The process of cooling and dehumidifying air which comprises causing air, which is to be conditioned, to circulate in heat exchange relation with a portion of an evaporator of a mechanical refrigerator and in heat exchange relation with another portion of the evaporator;

causing all of refrigerant, flowing from one of the portions to flow through the other whenever the refrigerator is in operation; and while refrigerant thus flows through the evaporator, causing a device to respond to a change in dry bulb temperature of the air to vary the rate of evaporation of refrigerant in one of said portions of the evaporator.

22. The process of cooling and dehumidifying air which comprises causing air, which is to be conditioned, to circulate in heat exchange relation with a portion of an evaporator of a mechanical refrigerator and in heat exchange relation with another portion of the evaporator; causing all of refrigerant, flowing from one of the portions to flow through the other whenever the refrigerator is in operation; and while refrigerant thus flows through the evaporator, causing a device to respond to temperature of the air to vary the effectiveness of one of said portions of the evaporator.

23. The process of cooling and dehumidifying air which comprises causing air, which is to be conditioned, to circulate in heat exchange relation with a portion of an evaporator of a mechanical refrigerator and in heat exchange relation with another portion of the evaporator; causing all of refrigerant, flowing from one of the portions to flow through the other whenever the refrigerator is in operation; and while refrigerant flows through the evaporator, causing a device to respond to temperature of the air to vary the rate of evaporation of refrigerant in one of said portions of the evaporator.

24. In an air conditioning system, in combination, a conditioning chamber, means connecting said conditioning chamber with a space to be conditioned, cooling means in said chamber, means for supplying cooling fluid to said cooling means, control means for varying the flow of cooling fluid through said cooling means, control means for varying the operation of said cooling fluid supplying means, temperature responsive means for substantially simultaneously actuating both of said control means, and humidity responsive means for actuating one only of said control means in one direction independently of said temperature responsive means.

25. A method of controlling the temperature and humidity of air consisting in circulating air to be conditioned in heat exchange relation with heat exchange surfaces, circulating refrigerant through said surfaces, causing sensible and latent heat to be removed from the air passing in contact with said surfaces when the dry bulb temperature of the air and absolute humidity per unit thereof exceed predetermined minimums, and causing the circulation of refrigerant to be restricted when the dry bulb temperature drops below the predetermined minimum to limit subsequent removal of sensible heat from the air and relatively increase subsequent removal of latent heat therefrom.

26. A system for conditioning air comprising in combination a conditioning chamber, heat exchange surfaces within the chamber, a refrigerant source, means for supplying refrigerant from said source to said heat exchange surfaces, means for circulating air from an enclosure to be conditioned through said chamber in contact with the surfaces, means operative responsive to temperature and humidity conditions within the enclosure for maintaining a maximum flow of refrigerant from said source through said surfaces whereby sensible and latent heat will be removed

from the air circulated in contact with the surfaces, means operative responsive to a drop in temperature of the air in the enclosure below a predetermined point for controlling the flow of refrigerant so that sensible heat removal from the air circulated in contact with the surfaces will be reduced and latent heat removal relatively increased, and means operative responsive to a drop in the humidity content of the air in the enclosure below a predetermined point to interrupt the circulation of refrigerant to said surfaces.

27. In an air conditioning system for producing desired conditions of temperature and humidity in the atmosphere of an enclosure, a conditioner casing, an evaporator within the casing, a compressor and condenser operatively associated with the evaporator to carry out a refrigeration cycle, means for circulating air through the casing, a temperature responsive device, a humidity responsive device, said devices being operative responsive to changes in temperature and humidity conditions within the enclosure, and means controlled by the temperature responsive device for limiting the flow of refrigerant to the evaporator whereby the suction pressure within the evaporator will be reduced relatively to increase the removal of latent heat from air passing through the casing in contact with a portion of the evaporator, said portion of the evaporator consisting of active surface wherein evaporation of refrigerant takes place, the remainder of the evaporator consisting of inactive surface wherein substantially no evaporation of refrigerant takes place.

28. A method of increasing reduction of the latent heat of air while decreasing reduction of the sensible heat thereof consisting in circulating refrigerant to be evaporated through heat exchange surfaces by compressing means, circulating air in contact with the heat exchange surfaces, continuing said last two steps until the temperature of the air is reduced to a predetermined minimum, then diminishing the supply of refrigerant to said surfaces without substantially affecting the operation of the compressing means to cause a decrease in pressure within said surfaces whereby a portion of said surfaces will be decreased in temperature to increase the rate of removal of latent heat from air contacting said portion of the surfaces, the remainder of the air passing in contact with the remainder of the surfaces having its latent and sensible heat content remain substantially unaffected.

29. A system for conditioning air comprising a compressor, a condenser, and an evaporator operatively associated to carry out a refrigeration cycle, a casing within which said evaporator is positioned, a fan for drawing air through the casing and delivering the air to an enclosure to be conditioned, means operative responsive to a drop in temperature and humidity of the air within the enclosure below predetermined minimums to interrupt the supply of refrigerant to said evaporator, means operative responsive to a drop in temperature below the predetermined minimum while the humidity of the air remains above the predetermined minimum to regulate the supply of refrigerant to the evaporator whereby a portion thereof will remain active and another portion substantially inactive, and means responsive to a rise in temperature above said minimum for causing the evaporator to become fully active.

ALONZO W. RUFF.
